(57) **CLAIM**

The ornamental design for set of buttons on motherboard, as shown and described.

DESCRIPTION

FIG. 1 is a perspective view of set of buttons on motherboard showing our new design;

FIG. 2 is a right side view of FIG. 1;

FIG. 3 is a top view of FIG. 1;

FIG. 4 is a front view of FIG. 1;

FIG. 5 is a bottom view of FIG. 1;

FIG. 6 is a left side view of FIG. 1;

FIG. 7 is a rear view of FIG. 1;

FIG. 8 is a top plan view showing the buttons of FIG. 1 disposed on a motherboard;

FIG. 9 is a top plan view showing an alternate location of the buttons of FIG. 1 disposed on a motherboard; and,

FIG. 10 is a partial front side view of FIG. 8.

The broken lines shown are for illustrative purposes only and form no part of the claimed design.
